VENTILATING SHUTTER

Carl J. Rindt, Chicago, Ill.

Application August 30, 1934, Serial No. 742,074

6 Claims. (Cl. 98—88)

The invention relates generally to ventilating shutters for covering the windows of a dwelling, and more particularly it relates to such shutters which are adapted to completely darken a room while providing for adequate circulation of air through the shutter.

Devices of this character find their greatest usefulness in the bedrooms of a home wherein night workers, children, or others must sleep during the daytime.

The primary object of the present invention is to provide a ventilating shutter of this character which is light and economical in construction, efficient in operation, easily applied and removed by unskilled persons, and of such a form and construction that it may be packed or stored easily and in a minimum of space.

Another object of the invention is to provide a new and improved device of this character of such a form that it may be constructed economically from a relatively inexpensive sheet material such as cardboard or similar composition sheets.

Another object is to provide a device of this character which embodies an improved ventilating structure adapted for construction from a sheet material and permitting adequate ventilation while excluding all light from the room.

Other objects and advantages will become apparent from the following description, taken in connection with the accompanying drawing, in which:

Fig. 1 is a perspective view illustrating a shutter embodying the features of the invention and in position over a window opening.

Fig. 2 is a central vertical sectional view of the shutter illustrated in Fig. 1.

Fig. 3 is a plan view showing the cardboard blank of the top section of the device.

Figs. 4 and 5 are plan views illustrating the cardboard blanks used to form the inner and outer walls of the bottom section.

Fig. 6 is a detail view of the fastening device employed.

While my invention is susceptible of embodiment in many different forms, I have shown in the drawing and will herein describe in detail one such embodiment, with the understanding that the present disclosure is to be considered as an exemplification of the principles of the invention and is not intended to limit the invention to the embodiment illustrated. The scope of the invention will be pointed out in the appended claims.

In the form chosen for disclosure herein the

invention is embodied in a shutter formed in two sections 10 and 11 which are illustrated in Fig. 1 in their cooperating relation wherein they cover a window opening 12 formed in the wall 13 of a room. It will be seen that the sections 10 and 11 overlie the side and upper edges of the opening 12 so as to form a light-excluding seal about the shutter, and the lower edge of the upper section 12 overlaps the upper edge of the lower section 11 on the outer side thereof so as to exclude light along this joint. Detachable fastening devices 14 are employed at spaced points about the outer edges of the two sections 10 and 11 to hold the same firmly against the wall 13 as will be herein-after described in detail.

The present two-section embodiment of the device is preferred and is of particular advantage because of its convenience in packing, installation and storage, and for the further reason that the smaller sheets required in this form may be purchased and processed more economically. The sheet material employed must, of course, have a reasonable amount of rigidity, must be opaque, and be easily workable, and preferably its surfaces are of a dark color so as to avoid reflection of light. Although many forms of composition board may be employed, I prefer to use a material known to the paper trade as corrugated board. This material is light in weight, inexpensive, has smooth surfaces, is easily worked in the production of the shutter, and possesses sufficient strength for shutters of ordinary sizes. Throughout the specification and claims I will employ the term cardboard a generic term embracing the material actually illustrated as well as all materials having substantially the characteristics above set forth.

As will be evident in Fig. 1 of the drawing, the present embodiment of the shutter has the upper and lower sections 10 and 11 of substantially the same size, the upper section 10 comprising simply a flat rectangular sheet of cardboard provided with spaced holes 15 about its side and upper edges to receive the detachable fasteners 14.

The lower section 11 in the present instances serves as the ventilator section and it is preferably of such a form that it may be constructed entirely of cardboard sheets to exclude light and yet provide a passage of considerable area for the entrance of air.

As shown in Fig. 2 of the drawing, the lower section 11 is shaped to a box-like form projecting inwardly of the room for a distance sufficient to allow for spaced inner and outer walls 55

16 and 17 which define a ventilating passage 18. The passage 18 has an inlet opening 19 which is preferably adjacent the bottom of the section 11 so as to avoid the necessity for unduly raising 5 the window sash 20, this opening being formed in the present instance by terminating the outer wall 17 short of the lower end of the section 11 so that the opening 19 is in the form of a relatively wide horizontal slot.

10 In this form, the passage 18 has an outlet opening 21 adjacent to the upper edge of the section 11, the opening being in the form of a horizontal slot as shown in Fig. 1, and by reason of its laterally offset relation to the inlet 19, it will 15 be evident that direct passage of light through the two openings is impossible. It has been found, however, that a slight amount of reflected light enters upwardly into the passage 18 and so tends to pass through the opening 21 20 to the ceiling of the room. The present invention provides simple and effective means to intercept such reflected light, this means comprising a flap or baffle 22 formed integrally along the upper edge of the opening 21 and adapted 25 to be bent outwardly as illustrated in Fig. 2 so as to lie in the path of such reflected light.

Similarly, a second flap 23 may be provided along the lower edge of the opening 21, this flap 30 preferably being bent inwardly to a slight extent so as to lie in the path of some of the innermost reflected rays. The flap 23 also serves to conceal the surface of the wall 17 opposite the opening 21, thus hiding from view a surface which in some instances may be slightly 35 illuminated by the light rays reflected back and forth within the passage 18. As a further safeguard, the lower edge of the outer wall 17 is preferably bent inwardly of the passage as at 24.

The ventilating unit 11 may, of course, be 40 permanently assembled by the manufacturer, but I prefer merely to form the various elements and pack and merchandise the same in a flat package which may be stored and handled with greater ease. In Figs. 4 and 5 the wall sections 16 and 17 are illustrated in their form as 45 flat blanks ready for packing or fabrication. As shown in Fig. 4, the inner wall section 16 has flap-like elements about all four of its edges, these elements being shaped to provide, in the 50 finished product, top, bottom and side walls 25, 26, and 27 respectively. At the ends of the top and bottom walls 25 and 26 flaps 28 are provided, suitable holes 29 being formed therein to register with similar holes 30 in the adjacent 55 side walls 27 so that an inexperienced user may secure the walls together with fasteners such as bendable staples 31 as shown in Fig. 2. In the present instance the lower flaps 28 are positioned within the side walls 27 while the upper flaps 60 28 which are of a relatively small size are folded onto the outside of the walls 27. It will be understood that in the formation of the blanks, the material is lined or crimped along each line of bending, this lining being indicated in Figs. 3, 4, 65 and 5 by dotted lines 32.

The blank for the outer wall section 17, as 70 shown in Fig. 5, also has flaps 33 along its side and top edges to provide for its association with the inner wall section. In the flaps 33, holes 34 are formed so that when the flaps are positioned 75 within and adjacent to the top and side walls 25 and 27 they may be secured in place by staples 31. The wall 17 is preferably positioned adjacent to the outer edges of the side walls 27 so that the flaps 33 may be concealed between the

inner and outer walls and an air passage of maximum area be provided. Preferably the flap 24 is permanently secured in its inwardly extending position and for this purpose apertured ears 24a are formed on the ends thereof adapted to be 5 secured by staples to the side flaps 33 of the wall 17.

In the form herein illustrated, the side walls 27 are slightly wider at their lower ends so as to provide a relatively large area in the air passage adjacent the lower end and thereby permit the use of the flap 24 without materially effecting the air flow. With the sloping inner wall 16, the outlet opening is positioned out of 10 the path of a large portion of the upwardly reflected light rays, such rays falling on the sloping inner surface of the wall 16.

To provide for mounting of the ventilating unit, flaps or flanges 35 are formed along the outer edges of the side walls 27 (Figs. 1 and 4), 20 holes 36 being formed in the flange 35 at spaced points to facilitate the application of the detachable fasteners 14. These fasteners are, in the present instance, in the form of screws having a pointed end section 37 screw-threaded so as to 25 permit attachment to the window frame 38 as shown in Fig. 6, with a different thread 39 on the outer end to receive a removable clamping nut or head 40.

As hereinbefore mentioned, the upper section 30 10 extends beneath the upper edge of the ventilating unit 11, and to insure a perfect light seal therebetween a flange 41 is provided along the edge of the top wall 25. This flange 41 is bent upwardly and by reason of the natural resiliency 35 of the material, its edge is firmly engaged with the inner surface of the section 10.

From the foregoing description it will be evident that the present device may be readily mounted over a window to insure the exclusion of 40 all light, it being noted that the bottom wall 26 has a substantial flat surface engagement with the inwardly projecting window sill 42. The steps involved in assembling and mounting the device are all simple in character so that no 45 mechanical skill is required of the user.

Of particular advantage is the construction of the device in such a form that it may be made from flat sheet material such as cardboard. This material being inexpensive, and the steps in the 50 manufacture being simple in character, the present device is one which is adapted for economical manufacture whereby to place it within the means of the majority of potential users.

I claim as my invention:

1. In a ventilating shutter, a ventilating unit 55 adapted to span and to be secured across a window opening and formed from an opaque relatively rigid and light sheet material to provide spaced inner and outer walls defining an air passage of substantial cross-sectional area therebetween, said outer wall being formed to provide a relatively large air inlet opening adjacent to one edge of said section and said inner wall being formed to provide a relatively large 60 outlet opening adjacent to the opposite side of said section, and an opaque light deflector on the edge of said outlet opening opposite from said inlet opening and adapted to project inwardly from said inner wall to intercept light rays reflected longitudinally through said passage between said openings.

2. In a ventilating shutter, a ventilating unit 70 adapted to span and to be secured across a window opening and formed from an opaque card- 75

board material to provide spaced inner and outer walls defining an air passage of substantial cross-sectional area therebetween, said outer wall being formed to provide a relatively large air inlet opening adjacent to one edge of said section and said inner wall being formed to provide a relatively large outlet opening adjacent to the opposite side of said section, a flap formed from such material positioned along the edge of said inlet opening which is adjacent to said outlet opening and bent into said passage to intercept reflected light, and a flap also formed from such material along the remote edge of said outlet opening and bent outward from said passage as a light intercepting means.

3. In a ventilating shutter, a ventilating unit adapted to span a window opening, said unit comprising a box-like inner wall section formed from an opaque relatively rigid and light sheet material to provide an inner wall with top, bottom and side walls adapted to extend from said wall toward the wall surface about a window, flanges on the edges of said side walls adapted to overlap said wall surface, said inner wall having a ventilating opening adjacent to its upper edge, and a light deflecting outer wall secured to and spanning the space between the opposite side walls of said inner wall section and in spaced relation to said inner wall, said outer wall having a light-excluding joint with one of said other walls along its upper edge and its lower end terminating short of said bottom wall to define an air inlet opening.

4. In a two-unit ventilating shutter, the combination of a ventilator section formed from an opaque and relatively rigid and light sheet material and having a light excluding ventilating passage therethrough, said section being adapted to span one portion of a window opening, a separate light excluding section formed from such a material and adapted to span the balance of the

opening, and a bendable flange along the edge of one of said sections adapted to overlie and press firmly against the adjacent surface of the other section to form a light tight joint therebetween.

5. A device of the character described formed from an opaque relatively rigid sheet material and formed to have a substantial flat surface engagement with the bordering surfaces about a window so as to effectually prevent the entrance of light about the edges of the device, said device embodying a ventilating section also formed from such sheet material and having a ventilating passage therethrough and means providing opaque baffles positioned in said passage and operable to intercept light rays and thereby prevent the entrance of light through said passage.

6. A ventilating device of the character described having a ventilating unit adapted to be secured in spanning relation to a portion of a window opening and formed from an opaque sheet material to provide spaced inner and outer walls defining an air passage of substantial cross-sectional area therebetween, said outer wall being formed to provide a relatively large air inlet opening adjacent to the lower edge of said section and said inner wall being formed to provide a relatively large air outlet opening adjacent to the upper edge of said section, said inner wall being positioned so as to slope outwardly toward its upper edge, a light deflector on the edge of said outlet opening opposite from said inlet opening and adapted to project inwardly from said inner wall to intercept light rays reflected longitudinally through said passage between said openings, and a light deflector on the upper edge of said inlet opening extending inwardly of said passage to intercept upwardly reflected light rays, the inner edge of said deflector being spaced from said inner wall so as to permit passage of a substantial air stream therebetween.

CARL J. RINDT.
